Filed Aug. 6, 1962, Ser. No. 214,953

7 Claims. (Cl. 58—125)

This invention relates to the construction and operation of a time piece, such as on the order of a clock. More particularly this invention has to do with the mounting and rotation of the hands of such a time piece.

It is a purpose and an object of this invention to provide an unusual construction of a time piece in connection with which the hands thereof are removably mounted and are rotated without being secured in a conventional manner to the driving or operating mechanism of the time piece.

It is a further object of this invention to provide a member forming a hand of a time piece having a pivot point at its point of rotational equilibrium, and a rotating member freely supporting said hand at said point and rotating said hand at a velocity relative to its own angular velocity.

It is also an object of this invention to provide a time piece in connection with which one hand is freely pivotally mounted upon the other hand and having rotative movement relative to the movement of said other hand.

It is still another object of this invention to provide a time piece whereby one hand at its point of rotational equilibrium is pivotally hung onto the other hand thereof with said other hand being pivotally hung at a point representing its point of rotational equilibrium, taking into consideration said first hand mounted thereon and said first hand being rotated by the rotation of said other hand.

Further it is an object of this invention to provide a time piece with hands thereof being freely mounted for rotation and not secured to a driving means in a conventional manner.

These and other objects and advantages of the invention will be fully set forth in the following description made in connection with the accompanying drawings in which like reference characters refer to similar parts throughout the several views and in which:

FIG. 1 is a view in front elevation of applicant's device with a portion thereof being broken away;

FIG. 2 is a view in vertical section taken on line 2—2 of FIG. 1 as indicated by the arrows;

FIG. 3 is a fragmentary view in vertical section taken on line 3—3 of FIG. 2 as indicated by the arrows;

FIGS. 4 and 5 show views similar to that in FIG. 3 in different positions;

FIG. 6 in a fragmentary view shows a detailed illustration of the operative principle of applicant's device on an enlarged scale;

FIG. 7 is a view similar to that of FIG. 1 showing a modification thereof;

FIG. 8 is a view in vertical section taken on line 8—8 of FIG. 7 as indicated by the arrows; and

FIG. 9 is a fragmentary view in vertical section taken on line 9—9 of FIG. 8 as indicated by the arrows.

Referring to the drawings and more particularly to FIGS. 1—5, one embodiment of applicant's invention is shown in the form of a wall mounted time piece 10 comprising a circular face portion or dial 11 which may be very decoratively formed, as of acrylic sheet material such as is sold under the trademarks of Lucite and Plexiglas. Spaced about the face of said dial adjacent the periphery thereof are indicia 13 representing indications of elements of time. Extending rearwardly of said dial 11 axially thereof is a cylindrical cup portion 14 arranged and constructed to receive and frictionally re-

2

tain therein a motor 14 having a casing suitable to be pressed thereto. Said motor will be connected to a source of current. Although an electrical motor is here indicated as a power source for the time piece, any suitable source of power may be utilized. Though not here shown, said time piece 10 will be mounted on a wall surface in a conventional manner.

Extending forwardly of said motor motor 14 through an aperture in said dial 11 is a drive shaft 16 having secured thereto a supporting member shown here in the form of pulley 18 having spaced retaining end plates or flange portions 19 and 20. Extending forwardly of said end plate 20 and integral therewith is a second pulley 21 eccentric to the axis of the pulley 18 and having at its free end a flange or end plate 22.

Mounted on said pulley 18 is a minute hand 25 and mounted on said pulley 21 is an hour hand 30. Said pulleys will be formed of a material having suitable frictional engagement with said hands.

Said hands 25 and 30 are most suitably formed of a homogenous material, such as of acrylic sheet material. The hands may be in the form of any desirable design, and for purpose of illustration they are here shown to be generally triangular in form. Said hands will be relative in size to one another as is customary in connection with time pieces.

With respect to the minute hand 25, its point of rotational equilibrium 35 will be determined and this will form the center of a circular hole or opening 26, or recess, which will have a periphery or circumference 27. Said hand 25 will be mounted on the pulley 18 by simply having said pulley disposed through the hole 26 and engaging a point on the circumference thereof which will form the suspension point 37 and this is particularly referred to as a reference point. This suspension point will always be a point of engagement with said circumference in vertical alignment with the point of rotational equilibrium and in effect relative to the point of suspension, the point of center of gravity of said hand has been lowered. Hence at the point of suspension which may be any point of the circumference of said hole or opening 26, the hand 25 will always be in a stabilized position and it will never be out of rotational equilibrium.

In the particular embodiment of the invention here illustrated, the shaft 16 will have a velocity of two revolutions per hour, as will also the pulley 18 integral therewith. Said pulley is here indicated as being three-fourths inches in diameter with the opening 26 being one and one-half inches in diameter.

With reference to the hour hand 30, formed therethrough is a circular hole or opening 31 the center 33 of which will be the point of rotational equilibrium thereof. Said hand will be positioned on the pulley 21 by having said pulley disposed through said hole 31 and engaging point 34 on the circumference 32 of said opening. Said point of engagement between said pulley and said circumference forms the reference point of suspension in identical manner as point 37 forms the reference point of suspension of said hand 25. The diameter of said opening 31 is here indicated as being one and one-half inches with the diameter of the pulley 21 being one-sixteenth inches for a ratio of twenty-four to one.

Operation

The principle of rotation of the hands of applicant's invention in a timepiece is herewith explained. With particular reference to the hand 25 as seated on the pulley 18, the pulley will have frictional engagement with the circumference 27 of the circular opening 26 of said hand. Hence as the pulley rotates it causes the rotation of the hand. The point of engagement of said pulley with the

circumference of the opening forms the suspension point 37 which is here indicated as a reference point and this will always be vertically aligned with the point of rotational equilibrium 35. Thus the hand will always be in a stable position relative to the suspension point. The suspension of the hand at the point 35 also provides a lowered center of gravity of the hand.

Referring to the diagrammatic view in FIG. 6, as the shaft 18 rotates to the right it causes a corresponding rotation of the hand 25 and thus there follow successive points of engagement between the pulley and said circumference. There will be an infinite number of successive points of such engagement at infinitesimal increments with each successive point forming a new point of suspension at the same reference point, that is, in direct vertical alignment with the center of the opening 26 which is the point of rotational equilibrium of the hand 25.

In the drawing, the points P1-P4 are reference points of engagement on the circumference 27 and the points R1-R4 are corresponding reference points of engagement on the pulley 18. The engagement between the pulley and the circumference is tangential and thus in effect there is a point of engagement. The reference points here shown are spaced at exaggerated intervals. Actually these points are spaced at infinitesimal increments. The relationship between the pulley 18 and the circumference 27 is a linear one. Thus with the ratio of the circumference of the opening 26 relative to the circumference of the shaft being 2:1 and the shaft rotating with a velocity of two revolutions an hour, the shaft will rotate twice for each rotation of the hand whereby the hand 25, forming the minute hand, will move about the dial 11 once each hour.

The hour hand 30 operates in a similar manner in connection with the pulley 31 as did the hand 25 with the pulley 18. The difference lies in the ratio between the size of the pulley 21 relative to the size of the circular opening 31. Here the ratio is 24:1. The pulley rotates twenty-four times for each rotation of the hand 30 about the face of the dial 11 to indicate the passage of twelve hours. The pulley rotates twice in moving said hand the interval to indicate the passage of one hour. The pulley 21 in being eccentric to the pulley 18 actually moves through a circular orbit.

Thus the hands 25 and 30 respectively in rotational equilibrium are moved through a succession of suspension points at a relative velocity with respect to one another to make up an accurate time piece.

The hands of applicant's time piece are always in perfect balance, hence there is no slippage or faltering in their movement and there results uniform rotation of the hands and accurate time being had.

Acrylic material has been used for the hands and pulleys. This has proved to be a very satisfactory homogeneous material which is readily balanced and there results a very satisfactory degree of frictional engagement between the hands and their respective pulleys.

Although the basic operating mechanism of applicant's time piece is the motor 14, yet the application of the motor in operating the hands comprises an unobvious means of driving the hands in a time piece. The result is a unique and distinctive time piece with the hands being readily removable, easily positioned without affecting the motor 14 in any way, and the hands may readily be exchanged for others of any desirable design or color.

Referring to FIGS. 7-9, a modification of applicant's invention is shown in which portions similar to those in the previous embodiment are indicated by like characters. Applicant's modified invention comprises a time piece 40 having a dial 11 having indicia 13 thereon and having a rearwardly extending cup-like portion 12 having frictionally secured therein a motor 14 having a drive shaft 16 extending forwardly of said dial 11 and having secured thereon a pulley 41 having spaced flanges 42 and 43 at either end thereof.

Hung onto said pulley 41 is a hand 45 representing the

75

minute hand of the time piece. Said hand is similar to the hand 25 and has a circular opening 46, or recess, therein having for its center the point 60 representing a point of rotational equilibrium, as will hereinafter be described.

The circumference of said opening 46 is indicated as being double that of said pulley 41 and with the shaft 16 and pulley 41 rotating at a velocity of two revolutions an hour, said minute hand 45 will make one rotation about the face of the dial 11 each hour. In FIG. 9, the reference point 65 is indicated as being the point of suspension at which said hand is supported on said pulley.

Integral with said hand 45 and extending outwardly therefrom is a pulley 51 secured to said hand at its hub portion 50, as by the use of an adhesive. Said pulley has an outer end flange portion 52.

Hung onto said pulley 51 is an hour hand 53 similar to the hand 30 previously described and having a circular opening 54 therein having a circumference 55. The reference point 61 indicated in FIG. 7 as being the center of said opening is also the point of rotational equilibrium of said hand.

Now to refer back to the hand 45, said reference point 60 is the point of rotational equilibrium of the hands 45 and 53 in combination with said hand 53 being supported by said hand 45 at a point eccentric to what otherwise would be its point of rotational equilibrium taken by itself.

With the pulley 41 having axial rotation, the pulley 51 will have orbital rotation with its path of movement describing a circular orbit. The ratio between the circumference of the pulley 51 and the circumference of the opening 54 indicated as being 12:1.

The principle of operation of the time piece 40 here described is identical with that of the time piece first above described. The difference present is a structural difference in that the hour hand 53 is suspended from the minute hand 45 instead of being mounted onto the same pulley which carries the minute hand.

The hand 45 makes a complete rotation about the face of the dial 11 to indicate the passage of one hour with each two revolutions of the pulley 41. Each revolution of the pulley 51 moves the hour hand 53 a distance to indicate the passage of one hour of time. When the pulley 51 has made twelve revolutions, the hand 53 will have been moved through one complete rotation to indicate the passage of twelve hours of time.

Both the structure and principle of operation of applicant's time pieces are believed to represent unique and unobvious differences with respect to conventional time pieces and there is provided a very distinctive and attractive product. Applicant's invention has proved to be very successful in operation.

It will of course be understood that various changes may be made in the form, details, arrangement and proportions of the parts, without departing from the scope of applicant's invention which, generally stated, consists in a device capable of carrying out the objects above set forth, in the parts and combinations of parts disclosed and defined in the appended claims.

60 What is claimed is:

1. A timing apparatus comprising an elongated member forming a hand, a circular opening in said hand, said opening having its center coincidental with the point of rotational equilibrium of said member, a pulley disposed through said opening axially thereof engaging the circumference thereof at a point vertically aligned with the center of said opening, said point forming a suspension point for said member, means rotating said pulley, said pulley in rotating causing the rotation of said member in engaging an infinite number of successive points on said circumference spaced at infinitesimal increments forming a succession of suspension points of said member, said suspension points being verti-

cally aligned with said point of rotational equilibrium.

2. A timing apparatus comprising
an elongated member forming a hand,
a circular opening in said hand,
said opening having its center coincidental with the
point of rotational equilibrium of said member,
a cylindrical supporting member of smaller diameter
than the diameter of said opening and extending axially therethrough engaging a point on the circum-
ference thereof,
said point of engagement being vertically aligned with
said point of rotational equilibrium,
means rotating said supporting member, and
said rotating supporting member having a certain lin-
ear relationship with said circumference and rotating
said hand by engagement with said circumference at
an infinite number of successive points thereon.

3. A timing apparatus comprising
an elongated member forming a hand,
a circular opening in said hand,
said opening having its center coincidental with the
point of rotational equilibrium of said member,
a cylindrical supporting member having a smaller cir-
cumference than that of said opening and having a
specific ratio thereto,
said supporting member being disposed axially through
said opening having a tangential engagement with
the circumference of said opening forming a point
of suspension,
means rotating said supporting member,
said supporting member rotating said hand by engage-
ment of successive points on the circumference of
said opening.

4. The structure set forth in claim 3,
a second hand,
a second supporting member integral with said first sup-
porting member,
said second hand having a circular opening therein
having the center thereof coincidental with the point
of rotational equilibrium of said member,
said second hand having a circumference having a
certain ratio to the circumference of said opening
of said second hand and being disposed through said
opening to engage a point on the circumference
thereof, and
said second supporting member rotating said second
hand by engaging successive points on the circum-
ference of the opening thereof.

5. A timing apparatus comprising
an elongated member forming a hand,
a circular recess in said hand,
said recess having its center coincidental with the point
of rotational equilibrium of said hand,

a cylindrical supporting member axially of said recess
engaging a point on the circumference thereof forming
a suspension point,
means rotating said supporting member, and
said supporting member rotating said hand by engage-
ment of successive points on the circumference
thereof.

6. A timing apparatus comprising
an elongated member forming a hand,
a circular opening in said hand,
a cylindrical supporting member,
said hand being hung onto said supporting member by
engagement of said supporting member with a point
on the circumference of said opening,
said hand having a cylindrical supporting member ex-
tending outwardly therefrom being integral there-
with,
a second hand,
said second hand having a circular opening therein,
said opening having a center coincidental with the point
of rotational equilibrium of said second hand,
said second hand being hung onto said second support-
ing member by engagement of said supporting mem-
ber with a point on the circumference of said open-
ing,
the center of said opening of said first hand being at
the point of rotational equilibrium of said first and
second hands taken in combination,
means rotating said first supporting member, and
said first supporting member rotating said first hand by
engaging successive points on the circumference of
the opening thereof, and said first hand rotating said
second supporting member to rotate said second
hand by engagement of successive points on the cir-
cumference of the opening of said second hand.

7. The structure set forth in claim 6,
said first and second supporting members respectively
having circumferential ratios relative to said first
and second openings of said first and second hands
whereby said hands are respectively rotated at
velocities relative to one another and relative to the
velocity of said first supporting member to measure
the passage of time.
